US0D1050042S

(12) **United States Design Patent** (10) Patent No.: **US D1,050,042 S**
(45) Date of Patent: ** Nov. 5, 2024

(54) **RESISTOR**

(71) Applicant: **Richardson Electronics, Ltd.**, Lafox, IL (US)

(72) Inventors: **Brian Christopher Gumino**, Lafox, IL (US); **Jeremy Winston Wilks**, Lafox, IL (US); **John Raymond Curran**, Lafox, IL (US)

(73) Assignee: **Richardson Electronics, Ltd.**, Lafox, IL (US)

(**) Term: **15 Years**

(21) Appl. No.: **29/865,714**

(22) Filed: **Aug. 9, 2022**

(51) LOC (14) Cl. **13-03**

(52) U.S. Cl.

USPC **D13/125**

(57) **CLAIM**

The ornamental design for a resistor, as shown and described.

DESCRIPTION

FIG. 1 is an upper perspective view of a resistor;

FIG. 2 is a lower perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines illustrate portions of the resistor and form no part of the claimed design.

1 Claim, 3 Drawing Sheets
